(57) **CLAIM**

The ornamental design for a portable luminaire, as shown and described.

DESCRIPTION

FIG. 1 is a front perspective view of a portable luminaire in accordance with an embodiment of the new design;

FIG. 2 is a front view thereof;

FIG. 3 is a top view thereof;

FIG. 4 is a bottom view thereof;

FIG. 5 is a rear view thereof;

FIG. 6 is a side view thereof;

FIG. 7 is a front perspective view of a portable luminaire in accordance with another embodiment of the new design;

FIG. 8 is a side view thereof;

FIG. 9 is a top view thereof;

FIG. 10 is a front view thereof;

FIG. 11 is a rear view thereof; and,

FIG. 12 is a bottom view thereof.

The broken line showing is for illustrative purposes only and forms no part of the claimed design.
